UNITED STATES PATENT OFFICE.

JOHN E. FRY, OF GIBSONBURG, OHIO.

SELF-HEATING SAD-IRON.

No. 880,514.

Specification of Letters Patent.

Patented March 3, 1908.

Application filed May 14, 1906. Serial No. 316,820.

To all whom it may concern:

Be it known that I, JOHN E. FRY, a citizen of the United States, residing at Gibsonburg, in the county of Sandusky and State of Ohio, 5 have invented a new and useful Self-Heating Sad-Iron, of which the following is a specification.

This invention has relation to self-heating sad-irons and it consists in the novel construction and arrangement of its parts as hereinafter shown and described.

The object of the invention is to provide a self-heating sad-iron from which the heat is permitted to escape in such a manner as not 10 to come in contact with the hand of the operator. In irons of this character much discomfort is caused by reason of the fact that the heat escapes around the sides of the iron and passes up along the hand of the operator. 15 The present invention avoids this disadvantage for when the iron is moved in one direction, the heat escapes out of the end thereof opposite to that located in the direction in which the iron is moving and when the iron 20 is moved in the opposite direction, the heat escapes from the iron in a similar manner. Thus the hand and arm of the operator is continually moved away from the heat which 25 is escaping from the iron. A means is also 30 provided for adjusting the air feed to the hydro-carbon burner of the iron.

In the accompanying drawing:—Figure 1 is a longitudinal sectional view of the self-heating sad-iron. Fig. 2 is a perspective 35 view of the handle portion of the iron, as shown in Fig. 1. Fig. 3 is a longitudinal sectional view of a modified form of the iron, and Fig. 4 is a perspective view of the forward portion of the iron handle, as shown in 40 Fig. 3.

The iron consists of the body portion 1 which is provided with the usual combustion chamber 2. Said chamber is closed at its upper edges by means of the removable 45 handle part 3. The said handle part is provided with the usual handle 4 below which is located a hand shield 5. The base of the said handle portion consists of the plates 6 and 7 which are located in planes parallel to 50 each other but spaced apart. In the form of the invention as illustrated in Figs. 1 and 2 the said plates 6 and 7 are not closed along their longitudinal edges and the bottom plate 7 is provided with a number of depending tubes 8 which when the handle portion 3

is in position upon the base 1 of the iron extend down into the combustion chamber 2 of the said body portion 1. The handle posts 9, 9 are made integral with the ends of the plates 6 and 7 and each post is provided with a vertically disposed funnel shaped aperture 10, the mouth of each aperture facing toward the respective end of the iron at which it is located. The hydro-carbon burner 11 is located within the combustion chamber 2 and is provided at its rear end with the air inlet 12. The valve 13 is mounted upon the rear end of the burner and is adapted to slip over the opening 12 in such manner as to regulate the size of said opening and the quantity of air which may pass therethrough. The needle valve 14 is located at the rear end of the burner and is adapted to regulate the flow of hydro-carbon which passes through the pipe 15 from the tank 16. The tank 16 is located in an elevated position at the forward end of the iron and the connecting pipe 15 passes along the entire length of the combustion chamber 2 where it is contained. The hydro-carbon is subjected to intense heat and is converted from a liquid to a gaseous state in which condition it is burned at the burner 11.

The circulation of air through the combustion chamber 2 and the removal of the products of combustion from said chamber is accomplished in the following manner: Presuming that the iron is being moved by the hand in a forward direction, cold air passes between the plates 6 and 7 and down through the depending tubes 8 into the lower portion of the combustion chamber 2 while the heat and products of combustion pass out of the funnel shaped aperture 10 facing the rear end of the iron. Thus the hand and arm of the operator move in advance of the heat and products of combustion as the same are liberated from the implement. When the iron is moved in a backward direction, the air is introduced into the combustion chamber in the manner as above described but instead of passing out of the rear aperture, the heat and products of combustion pass out through the aperture 10 nearest the pointed end of the iron. This circulation of air and sweeping out of the combustion chamber 2 is accomplished owing to the fact that the heat will endeavor to seek the highest possible level, consequently the flame from the burner 11 will pass up against the under side of the

plate 7 and the products of combustion will pass out of either of one or another of the apertures 10. The vacuum thus created is supplied by air which enters into the space 5 between the plates 6 and 7 and passes down through the tubes 8, 8 and is liberated in the combustion chamber 2 near the bottom thereof in the manner as above described.

In the form of the invention as illustrated 10 in Figs. 4 and 5 the longitudinal edges of the plates 6 and 7 are closed by the walls 17, the openings 18, however, being left at the forward end and the opening 19 provided at the rear end of the handle portion of the iron. 15 The handle posts 13, 13 are provided with the funnel shaped apertures 20 to the lower ends of which are attached the depending sleeves 21. The perforations 22 in the plate 7 afford a means of communication between 20 the combustion chamber 2 and the space between the plates 6 and 7.

The circulation of air through the iron in the form of the invention as illustrated in Figs. 3 and 4 is as follows: Presuming that 25 the iron is being moved in a forward direction, the cold air enters the forward aperture 20 passes down through the sleeve 21 into the combustion chamber 2. The warm air and products of combustion pass up through the 30 perforations 22, 22 and out at the rear end of the iron through the opening 19. When the movement of the iron is reversed in direction, the cold air passes down through the aperture 20 located adjacent the rear end of the 35 iron and into the lower portion of the combustion chamber 2. The products of combustion pass up through the openings 22, 22 and out through the openings 18 located at the forward ends of the walls 17 connecting 40 the longitudinal edges of the plates 6 and 7.

It will thus be seen that in either form of construction that the circulation of air

through the iron and the liberation of the products of combustion therefrom are accomplished in substantially the same manner. 45 That is to say that the products of combustion and heat pass out of the iron behind the hand and arm of the operator while the method of introducing the air into the iron in the two forms of the inventions differs somewhat by reason of the fact that the parts, although similar in construction differ 50 slightly as to their respective location.

Having described my invention, what I claim as new and desire to secure by Letters 55 Patent is:—

1. As a new article of manufacture, a handle for sad irons comprising two spaced parallel plates marginally in communication with the atmosphere, handle posts integral with 60 the plates and provided with oppositely discharging air channels that extend from the lower plate to points intermediate of the ends of the posts, and open-ended tubes carried by the lower plate and disposed at right angles 65 thereto and communicating with the space between the plates.

2. A sad iron comprising a body having a combustion chamber, a burner therein, and a handle comprising two spaced parallel plates 70 marginally in communication with the atmosphere, handle posts carried by the plates and provided with oppositely-discharging air channels that extend from the lower plate to points intermediate the ends of the posts, 75 and open-ended tubes carried by the lower plate and disposed on each side of the burner.

In testimony that I claim the foregoing as my own, I have hereto affixed my signature in the presence of two witnesses.

JOHN E. FRY.
